UNITED STATES PATENT OFFICE.

MELVILLE A. CLARK, OF SYRACUSE, NEW YORK.

HARP.

1,406,347.

Specification of Letters Patent. Patented Feb. 14, 1922.

Application filed January 27, 1919. Serial No. 273,284.

To all whom it may concern:

Be it known that I, MELVILLE A. CLARK, of Syracuse, in the county of Onondaga, in the State of New York, have invented new

5 and useful Improvements in Harps, of which the following, taken in connection with the accompanying drawings, is a full, clear, and exact description.

This invention relates to certain improvements in harps similar in some respects to that shown in my pending application No. 119,194, filed September 9, 1916, in so far as it is directed to relatively small harps having a proportionately larger number of 15 strings than the standard large harps, and also to the use of hand operated means operable from either side of the neck of the harp for fretting various groups of strings of like denomination, reference being had to 20 my Patent 1,351,468 issued August 31, 1921.

The distinctive objects, however, of my present invention are:—

First, to place the fret-operating handles along the lower edge of the neck some distance below the system of frets so that they 25 may be quickly and conveniently adjusted by a slight movement of either hand from its playing position.

Second, to progressively raise the pitch of 30 the same group of strings at least two half-tones above their normal pitch by continued rotary movement of a single hand-piece in the same direction.

Third, to enable the operating means for 35 the movable frets to automatically lock the frets in their fretting positions.

Fourth, to permit the movable frets of either row for strings of like denomination to be operated by either hand from either 40 side of the neck of the harp.

Fifth, to provide the opposite faces of each fret-operating handle with distinctive markings which will enable the operator to 45 visually determine at a glance the positions of the various groups of frets of either row.

Sixth, to make the handles more or less luminous whereby the markings thereon may be readily seen in the dark, and

Seventh, to provide the several strings 50 with visible markings arranged along a line to indicate the position at which the strings may be engaged by the fingers to produce the most effective tones.

Other objects and uses relating to specific 55 parts of the instrument will be brought out in the following description.

In the drawings—

Figure —1— is a side elevation of the harp embodying the various features of my invention.

Figure —2— is a fragmentary elevation of a portion of one of the strings showing the harmonic fingering mark thereon.

Figure —3— is an inverted plan of the system of movable frets including the individual operating mechanisms for the several groups of strings of like denomination and the supporting frame for said frets and mechanism, portions of the protruding ends of the tuning pins on the neck of the harp being also shown.

Figure —4— is an enlarged transverse vertical sectional view through the neck of the harp taken on line 4—4, Figure —1—, showing one side of the handles of one of the fret operating mechanisms.

Figure —5— is a reverse face view of the same operating handles shown in Figure —4— and crank shaft upon which they are mounted.

Figure —6— is a transverse vertical sectional view through the neck of the harp as seen in Figure 8, showing more particularly the bearings for the fret spindles and the relative positions of the link mechanisms.

Figure —7— is an enlarged longitudinal vertical sectional view through the neck of the harp showing the link connections between the several crank shafts for operating the various groups of strings of like denomination, the adjacent portions of the column, front post and strings being shown in elevation.

Figure —8— is an enlarged longitudinal vertical sectional view through the portion 95 of the neck of the harp showing more particularly the means for progressively operating the upper and lower rows of frets, the dotted lines indicating the different positions of the crank shaft and links in effecting the adjustment of the frets from their normal positions, shown by full lines.

The frame of the harp is substantially triangular in outline and consists of a rear column —1— and front post —2—, and a neck —3— connecting the upper ends of the column —1— and post —2— both of which latter are rigidly united at the bottom to form a unitary structure, the column —1— being provided with the usual sounding board —4—.

The strings as —5— are disposed in one

and the same plane and have their lower ends attached in the usual manner to the longitudinal center of the sounding board —4—, while their upper ends are disposed 5 at one and the same side of the neck —3—, and are attached to suitable tuning pins —6— which are journaled in appropriate bearings in the upper section of the neck —3—, the latter being provided with the 10 usual rests —7— close to the tuning pins —6— and across which the strings are tightly drawn for proper tensioning and spacing purposes.

In order that the maximum number of 15 strings may be employed the tuning pins are continued throughout practically the entire length of the neck of the harp so that the system of strings extends practically the entire length of the column and beyond 20 the front edges of the upper portion of the post as shown more clearly in figure —1—, thus affording a relatively wide range of tones in a harp of comparatively small size.

The majority of the intermediate strings 25 are provided with visible markings —8— arranged at points along a line most suitable for engagement of the strings by the fingers for producing the desired tone quality or harmonics, and is particularly 30 useful for beginners in learning the proper fingering of the strings.

The frame of the harp is usually made from a selected quality of wood and in this instance the lower portion of the neck is 35 chambered or partially cut away at —9— to receive portions of the operating mechanisms for the frets, but the neck is otherwise reinforced by metal plates —10— which are secured along their upper edges by screws 40 —11— to opposite faces of the neck —3—, and extend downwardly therefrom in transversely spaced relation to form a supporting frame for the frets and their operating mechanism.

45 In order that the pitch or key of the various strings may be varied at least two semitones from their normal pitch or key two distinctive rows of fretting devices one above the other are provided so that each 50 string may be engaged or fretted at two different points in its length to produce a corresponding number of changes in the effective vibratory length of said string.

These fretting devices are substantially 55 identical in that each comprises a rock shaft —12— journaled in suitable bearings in the opposite plates —10—, and having its end adjacent to the strings provided with a head —13— having one or more fretting pins 60 —14— for engagement with the corresponding string as the shaft —12— is rocked about its axis in the manner hereinafter described, the diameter of the heads —13— being gradually increased as the length of 65 the strings increases, the heads for the inter-

mediate and longer strings being usually provided with two pins —14— while the heads for the shorter strings near the column —1— are preferably provided with a single pin as shown more clearly in figure —1—.

70

One end of each rock shaft is preferably tapered at —15— for wedging engagement in its bearing in the adjacent plate —10—, the opposite end being journaled in a bushing —16— containing a spring —17— by 75 which the rock shaft —12— is spring pressed endwise to frictionally bind the cone —15— in its bearing, and thereby assist in holding the fretting device in adjusted position.

Each rock shaft —12— is provided with 80 a crank arm —18— rigid thereon, those for the fretting devices in each row for the strings of like denomination being connected together by links —19—, whereby the operation of any one of the fretting devices 85 of either row will cause the simultaneous operation of all the fretting devices for all of the strings of like denomination in the same row.

It, therefore, follows that the pitch of any 90 one set of strings of like denomination may be raised one half tone above normal by the operation of the corresponding fretting devices of the upper row, and that by adjusting the corresponding set of fretting devices of the lower row, the pitch of the same strings will be raised another half tone by reason of the changes in the effective vibratory lengths of said strings.

95

The fretting devices of the upper row are 100 arranged to raise the pitch of their respective strings a half tone while those of the lower row are arranged to further raise the pitch of the same strings another half tone, the various strings being normally tuned a 105 half tone below the "natural" key in which the instrument is to be played so that in order to play in that key it becomes necessary to first shift the fretting devices of the upper row.

110

If any group of strings are to be sharpened it is simply necessary to shift the corresponding fretting device of the lower row by the continual movement of the hand-piece another step in the same direction.

115

On the other hand if any group of strings are to be flattened it is simply necessary to release and restore the corresponding fretting devices of both rows at which time those strings will produce the tones at which they are normally set.

In the use of two fretting devices for engaging the same string at different points in its length, as just previously explained, it is desirable to provide means for operating 125 them in sequence, as for example the upper one first, followed by the operation of the lower one, or in other words the operation of the upper fretting devices of each group of strings followed by the operation of the 130

lower set of fretting devices corresponding to the same group through the medium of a single hand-rock-shaft or equivalent hand-operated device and suitable means for transmitting motion from said rock shaft to the particular sets of fretting devices of both rows which are adapted to be operated in sequence.

For this purpose is provided a plurality of in this instance seven rock shafts —20—, one for each group of strings of like denomination, journaled in the opposite plates —10— preferably below the lower row of fretting devices, as shown more clearly in Figures 4, 7, and 8, each provided with a crank arm —21— connected by a link —22— to one of the crank shafts —12— of one set of the lower fretting devices corresponding to a particular group of strings, whereby the rocking of said shaft —20— from its normal position through a predetermined arc will cause a similar rocking movement of the corresponding set of rock shafts —12— of the lower row through the medium of the lower connecting links —19—.

The pins —14— of the lower row of the fretting devices are normally positioned in such relation to their strings that this initial rocking movement of the rock shafts —20— will effect the movement of the corresponding fretting devices of the lower row through only a part (in this instance substantially half) of its complete arc of movement necessary to engage the adjacent strings, but on the other hand is sufficient to effect the adjustment of the upper fretting devices for the same strings to their fretting positions.

For this latter purpose one of each group of the lower row of rock shafts —12— (preferably the group nearest the post —2—) is provided with a cam —23— for engaging and operating a bell-crank lever —24— by which motion is transmitted to the corresponding rock-shafts —12— of the upper row.

In other words the first seven rock shafts —12— from the left of the upper row are directly over their companion rock shafts —12— of the lower row, and are provided with additional crank arms —25—, each of which is operatively connected by its bell-crank lever —24— to its companion cam —23— on the lower rock shaft —12—.

These bell-cranks are mounted on suitable cross pins —26— which are supported in the opposite plates —10—, the upper end of said bell-cranks being engaged with pivotal pins —27— on their respective crank arms —25—, while their lower ends are provided with bearings —28— riding against the faces of their respective cams —23—.

Referring now to Figure —8— it will be seen that as one of the rock shafts —20— is rocked from its normal position through

practically a quarter turn it will transmit similar rocking movement to one of the lower rock shafts —12— through the medium of its link —22—, and that similar rocking movement will be transmitted to the group of lower shafts —12— corresponding to the strings of like denomination through the medium of the lower links —19—, thereby operating the corresponding cam —23— against the lower end of the bell-crank lever —24— and causing the latter to shift the companion upper fretting device to its fretting position, and through the upper links —19— will cause the operation of the upper fretting device of the same group. 80

It is now clear that one group of the upper row of fretting devices have been shifted to their fretting positions at which time the lower end of the corresponding bell-crank lever —24— will have been engaged by a concentric portion of the cam —23— which will serve to hold the previously adjusted upper fretting members in their fretting positions, while at the same time the rock shafts of the corresponding lower group 90 may be rocked to a still greater arc by continuing the movement of its operating shaft —20— in the same direction through practically another quarter turn, thereby shifting the lower group of fretting devices to their 95 fretting position while the corresponding upper group remain as previously adjusted thereby causing the same strings to be fretted at different points in their lengths.

Any suitable means may be provided for 100 frictionally holding the fretting device and their operating means in their adjusted positions, said means consisting in this instance in providing each of the shafts —20— with a notched-disc —30— co-operating with a 105 spring —31— for engaging in said notches, as shown more clearly in Figure —8—.

By reversing the operation of the shaft —20— the fretting devices and their operating means may be restored to their normal positions aided by a suitable retracting spring —32— Figures —7— and —8—.

Each of the rock shafts —20— preferably extends beyond the outer faces of the opposite plates —10— and is provided with 115 duplicate handles —33— one at each end to permit the fretting devices to be operated by either hand from either side of the harp, as may be most convenient to the operator when playing. 120

These handles are preferably flat and their opposite faces are distinctive by different color, as for example, white and black, as shown in Figures —4— and —5—, the white sides facing the operator 125 when the fretting devices are in their normal positions, and when adjusted to set the fretting devices of the upper row the handles will be edgewise toward the operator by the first quarter turn or when turned 130

through an arc of substantially 180° for adjusting the lower fretting devices to their fretting position the black sides will be presented to the operator, and it therefore follows that he can determine at a glance the position of the fretting devices of either row.

The handles on the several rock shafts —20— are lettered to correspond to the 10 denominations of the different groups of strings which they are to control and these letterings are preferably made luminous by luminous paint or other luminating means by which the keys may be readily distinguished in the dark and which renders the instrument particularly useful in trenches and other places where light is excluded.

Another important feature of the invention lies in the means by which the operating mechanism for the several groups of fretting devices may be automatically locked in its adjusted position and for this purpose the ends of the links —22— which are connected to the crank arms —21— of 25 the rock shafts —20— are curved in such a manner as to allow the pivotal connection of those parts to assume a "dead-center" position, and also to limit their movement beyond such position, as shown more clearly 30 by dotted lines in Figure —8—.

In operation, assuming that the strings are normally "flatted" or tuned a half tone below the "natural" in which the selection is to be played whereupon the handles —33— 35 may be turned a quarter turn in the direction indicated by dotted lines Figure —8— thereby adjusting all of the frets and bringing the strings to the natural key, then if any one group of strings are to be flatted 40 it is simply necessary to restore the corresponding rock shaft —20— and fretting device operated thereby to their normal position by a slight turning movement of one or the other of the handles —33— on the 45 ends of said rock shaft.

On the other hand if it is desired to sharp 50 any particular group of strings it is necessary to turn the corresponding rock shaft —20— through another quarter turn from the position to which it had been previously 55 adjusted to bring the strings to the natural key.

From the foregoing description it will be readily seen that the sharpening or flattening 60 of any group of strings may be easily and quickly effected by a slight turn of one or other of the handles —33— of the rock shafts corresponding to the strings to be fretted.

It will be noted that the rock-shafts 65 —20— and their operating handles —33— are arranged in close proximity to the lower edge of the neck —3— and some distance below the system of fretting devices which 70 brings the handles as closely as possible to

the hands of the player so that the fretting devices may be easily and quickly adjusted by a slight movement of either hand from the strings to the handles without appreciable break or omissions in the selection 75 or inconvenience to the operator.

What I claim is:

1. In a double action harp, two fretting actions, hand operated actuating means for one of the actions mounted on the neck of 75 the harp, and means for transmitting motion from the last named action to the other action.

2. In a double action harp, a plurality of fretting actions, hand operated means on 80 the neck of the harp for operating one of said actions, and means actuated by the last named action for causing the frets of another action to engage its strings before those of said last named action engages its strings. 85

3. In a double action harp, the combination of upper and lower fretting actions, hand operated means on the neck of the harp for operating the lower action and means actuated by the lower action for 90 operating the upper action to its fretting position earlier than the lower action.

4. In a double action harp, lower and upper fretting devices for the same string, hand operated means mounted on the neck 95 of the harp and adjustable to one position for causing a limited movement of one of the devices before engaging the string and to another position for causing said fretting device to engage the string, and means actuated by the first limited movement of said fretting device for causing the other fretting device to engage the string. 100

5. In a double action harp, lower and upper fretting devices for engaging one and 105 the same string, hand operated means mounted on the neck of the harp and adjustable to one position for causing a limited movement of the lower fretting device before engaging a string and to another position 110 for causing said fretting device to engage the string, and means actuated by the first named adjustment for causing the upper fretting device to engage the string. 115

6. In a double action harp, lower and upper fretting actions, operating means for one of the actions mounted on the neck of the harp, a cam actuated by the last named action, and means actuated by the cam for operating the other action. 120

7. In a double action harp, the combination of lower and upper fretting actions, operating means for the lower action mounted on the neck of the harp, and means actuated by the lower action for moving the upper action to its fretting position before the lower action reaches its fretting position. 125

8. In a double action harp, the combination of lower and upper fretting actions, hand operated means mounted on the neck 130

- of the harp for adjusting the lower action to its fretting position and automatically locking it in that position, and means actuated by the lower action for moving the upper action to its fretting position and automatically locking it in that position before the lower action reaches its fretting position.
9. In a double action harp, a lower set of 10 fret operating spindles and an upper set of fret operating spindles for strings of like name rotatably mounted on the neck of the harp and provided with crank arms, links connecting the crank arms of the lower spindles, additional links connecting the crank arms of the upper spindles, a hand operated crank-shaft journaled on the neck of the harp, a link pivotally connected to the crank-shaft 15 and to one of the crank arms of the lower set of fretting spindles for adjusting the lower set of spindles to their fretting positions as the crank-shaft is adjusted to a certain position, said crank-shaft and link 20 connected thereto being provided with operative means for locking the lower ac-
- tion in its fretting position, and means actuated by the rotary adjustment of one of the lower spindles for adjusting the upper action to its fretting position before the lower action reaches its fretting position.
10. In a harp of the character described, the combination of a movable fret and operating means therefor including a rock-shaft 25 extending transversely of the neck of the harp and handles on opposite ends of the rock shaft.
11. In a harp of the character described, movable frets for engaging the same string at different points in its length and means 30 including a handle adjustable to different positions for operating said frets in sequence, said handle having its opposite faces distinctive and arranged to successively face the operator in its different 35 positions.

In witness whereof I have hereunto set my hand this 17th day of January, 1919.

MELVILLE A. CLARK.

Witnesses:
